LASTING MACHINE

Charles G. Brostrom, Salem, Mass., assignor to
 United Shoe Machinery Corporation, Borough
 of Flemington, N. J., a corporation of New
 Jersey

Application January 17, 1940, Serial No. 314,258

65 Claims. (Cl. 12—7)

This invention relates to lasting machines, and is herein illustrated as embodied in a machine particularly intended for use in lasting the sides of shoes along their ball portions, although it will be understood that in various novel aspects the invention is not limited to means for operating on shoes in those particular locations.

An object of the invention is to provide a machine for lasting in a quick and effective manner the side portions of a shoe extending from the portions customarily lasted in the toe-lasting operation to the portions lasted in the shank-lasting operation. To this and other ends, there is herein disclosed a novel machine organization in which various features of the invention are embodied, comprising a rotary lasting device having a gripper for gripping the margin of an upper and pulling the upper and also means for laying the margin of the upper inwardly over an insole in position to adhere to the insole when cement is used to secure the upper in lasted position, the device being operated by power upon actuation of a clutch and being rotated completely about its axis in the lasting operation. In the construction shown the gripper is closed on the margin of the upper by a treadle which by further movement thereafter serves to start the power operation of the machine while holding the gripper yieldingly closed. Upon the starting of the machine, the gripper is held by a yieldable latch temporarily against rotation while the overlaying means by its rotation approaches the margin of the upper, and at this time a member which engages the insole is operated automatically to move the last relatively to the gripper in a heightwise direction and thus cause the gripper to pull the upper. The overlaying means then forces the gripper also to rotate, so that it first pulls the upper inwardly over the insole and is then released by the yieldable latch, whereupon the gripper opens and the insole-engaging member is retracted to permit reverse heightwise movement of the last into position to render the overlaying means, which acts as a wiper, effective to press the margin of the upper firmly on the insole as it wipes it inwardly over the insole. In the construction shown the last is thus moved reversely heightwise by the operator when permitted by the insole-engaging member, the last and shoe being further controlled by a shoe rest which engages one side of the shoe to prevent its movement in a widthwise direction by the lasting means acting on the upper at the other side of the shoe. In accordance with one of the features of the invention, the shoe rest is initial-

ly yieldable to permit the shoe to be positioned by the operator in the best relation to the gripper and is thereafter locked against further yield to provide a firm support for the shoe.

As a further feature the invention, in one embodiment herein disclosed, provides novel upper-gripping and pulling means whereby a gathering of the margin of the upper is effected to distribute the wrinkles evenly along the convexly curved edge of the shoe bottom. As illustrated, the upper is gripped by a plurality of pairs of jaws spaced from one another lengthwise of the edge of the upper, and relative movement of the different pairs of jaws to gather the margin of the upper is effected at the time when the last is moved heightwise in the manner above described to cause the jaws to pull the upper.

The above and other features of the invention, including various novel details of construction and combinations of parts, will now be more particularly described with reference to the accompanying drawings and thereafter pointed out in the claims.

In the drawings,

25 Fig. 1 is a view in right-hand side elevation of a machine in which the invention is embodied, with parts broken away;

Fig. 2 is a plan view of the machine, with parts broken away;

30 Fig. 3 shows a portion of the machine in right-hand side elevation, with a part in section on the line III—III of Fig. 2 and with other parts broken away;

Fig. 4 is a section on the line IV—IV of Fig. 3;

35 Figs. 5, 6, 7 and 8 are views similar to Fig. 3, or to portions thereof, showing the parts in different positions which they assume in the course of the lasting operation;

Fig. 9 is a view generally similar to Fig. 3, showing a modification;

Fig. 10 is a section on the line X—X of Fig. 9, with parts omitted; and

Fig. 11 is a section on the line XI—XI of Fig. 9, with parts omitted.

45 The machine comprises a column 2 on which is supported a head 4 having a depending cylindrical portion 6 vertically adjustable in the column. Rotatably mounted in brackets 8 and 10 (Fig. 2) secured to the head 4 is a shaft 12 on which is mounted a rotary lasting device 14 including a segmental member 16 pinned to the shaft, this member being provided with a rim 18 concentric with the axis of the shaft and formed to extend a substantial distance, preferably about two inches, lengthwise of the shaft.

The member 16 extends considerably more than half way around the shaft 12, and between the opposite end faces 20 and 22 of the rim 18 is a recess 24 (Fig. 3) in which is located, as part of the rotary lasting device 14, a gripper 26 for gripping the margin of the upper of a shoe supported horizontally on its side upon a shoe rest 28 controlled as hereinafter described. This gripper, in the construction shown in Figs. 1 to 8, inclusive, comprises three jaws 30 (Figs. 3 and 4) arranged in a series lengthwise of the edge of the shoe bottom for engaging the inner face of the upper materials, and a single jaw 32 arranged to engage the outer face of the upper materials and to cooperate with the three jaws 30 to grip the upper. The upper-gripping face of the jaw 32 and the cooperating gripping faces of the jaws 30 are curved lengthwise of the shoe in general similarity to the curvature of the edge of the shoe bottom along the ball portion of the shoe. The three jaws 30 are formed, respectively, as portions of arms 34 extending inwardly toward the shaft 12 and pivotally mounted at their inner ends on a pin 36 which is supported in spaced lugs of a yoke member 38 provided with spaced arms 40 which are pivotally mounted on the shaft 12. A portion of this yoke member extends outwardly past the end face 22 of the rim 18 and is provided with a thin curved extension 42 overlapping the end portion of the rim. The three gripper-jaw arms 34 are controlled, respectively, by fairly strong springs 44 seated in recesses in the arms and in other recesses in the yoke member 38, so that each of the three gripper jaws 30 is independently yieldable in response to the upper-gripping pressure applied by the jaw 32 to allow for variations in the thickness of the upper materials. Movement of each arm 34 in one direction, in response to pressure of its spring 44 thereon, is limited by a pin 46 (Fig. 3) mounted in the yoke member 38 and arranged to engage a lug 48 on the arm. Since the yoke member 38 is pivotally mounted by means of its arms 40 on the shaft 12, the construction is such as to permit relative movement of the yoke member and the segmental member 16 about the axis of the shaft, as more particularly hereinafter described, the yoke member, however, being held normally in a position determined by its engagement with an edge face 50 on the member 16 by means of a spring 52 which is connected to this member and the yoke member.

The gripper jaw 32 is secured to a pair of arms 54 connected together in fixed relation to each other by a threaded stud 56, a spacing sleeve 58 being mounted on this stud between the arms. At their rear ends the two arms 54 are pivotally mounted on the shaft 12 between the hub of the member 16 and the previously mentioned arms 40 of the yoke member 38. One of the arms 54 has extending upwardly therefrom a lug 60 provided with a pin 62 to which are connected oppositely extending springs 64 and 66 also connected, respectively, to pins 68 and 70 on the member 16. These springs cooperate to position the jaw 32 initially at some distance from the end face 20 of the rim 18 and at some distance from the jaws 30 so that the margin of the upper materials may be readily inserted between the opposed jaws. For moving the jaw 32 into upper-gripping position there is provided a hook-shaped latch 72 arranged to engage an angularly shaped extension 74 on the left-hand end of the stud 56. The latch 72 is pivotally mounted at 75

its lower end for limited movement about a pin 76 on the upper end of a bar 78 which is vertically movable in a bracket 80 (Figs. 1 and 2) fastened on the previously mentioned bracket 10. Fastened on the front face of the latch 72 is a leaf spring 82 the lower end of which is arranged to engage the front face of the bar 78 to maintain the latch in proper position to engage the extension 74 and swing the jaw 32 into upper-gripping position in response to downward movement of the bar 78, the spring being yieldable to permit the extension 74 to pass the latch near the end of the rotary movement of the lasting device. For thus moving the bar downwardly there is pivotally connected to its lower end a downwardly extending rod 84, and fastened on the lower end of this rod is a sleeve member 86 into which extends the upper end portion of a rod 88 connected at its lower end to a treadle 90, the treadle being pivotally mounted at 92 on the column 2 and being depressible against the resistance of a spring 94. A pair of springs 96 are connected at their upper and lower ends, respectively, to the sleeve member 86 and to a collar 98 fast on the rod 88. It will thus be seen that when the treadle 90 is depressed it acts through the springs 96 to impart downward jaw-closing movement to the bar 78 and the latch 72. By means hereinafter described the segmental member 16 and the yoke member 38 are prevented from turning in a counterclockwise direction, as the parts are viewed in Fig. 3, at the time when the jaw 32 is thus moved by the treadle into upper-gripping position, so that after the jaw has gripped the upper it is held substantially stationary. The treadle 90, however, may be further depressed against the resistance of the springs 96, the rod 88 moving downward relatively to the sleeve member 86, and by such tensioning of the springs 96 as results from this movement of the treadle the jaw 32 is pressed with increasing force yieldingly against the upper. The purpose of such further downward movement of the treadle is to start the power operation of the machine and thus to cause the lasting device 14 to be rotated in a counterclockwise direction by means which will now be described.

Fast on the shaft 12 is a sprocket wheel 100 driven by a chain 102 from another sprocket wheel 104 rotatably mounted on a rod 106 which is fast in a bracket 108 secured to the head 4. Formed integral with the sprocket wheel 104 is a gear wheel 110 which, through an idle pinion 112 (Fig. 1) on the bracket 108, is driven by a pinion 114 rotatable on a rod 116 fast on the head 4. The pinion 114 is coupled to one member 118 (Fig. 2) of a friction clutch 120, this member having a hub portion 122 on which is rotatably mounted a sprocket wheel 124 connected by a chain 126 to a sprocket wheel 128 driven by an electric motor 130 at the base of the column 2. Mounted between a flat face of the member 118 and one side of the sprocket wheel 124 is a leather washer 132, and mounted between the other side of the sprocket wheel and an annular plate 134 rotatable with the member 118 is another leather washer 136. The plate 134 is mounted on the heads of screws 138 which are threaded in the hub portion 122 of the member 118, so as to permit the plate to move relatively to the member 118 lengthwise of the rod 116. On its outer face the plate 134 is engaged by a metal washer 140 between which and the hub 142 of an arm 144 is a ball bearing 146,

The hub 142 is provided on one end with a series of teeth 148 having end faces inclined relatively to the axis of the rod 116, these inclined faces being engaged by similarly inclined faces of teeth 150 formed on a collar 152 which is keyed to the rod 116 and is confined on the rod by nuts 154. Accordingly, when the arm 144 is swung in a downward direction its hub portion 142 is forced along the rod 116 by the teeth 150 and acts through the washer 140 to force the annular plate 134 toward that face of the member 118 which engages the washer 132. By compression of the two washers 132 and 136 in this operation the continuously driven sprocket wheel 124 is connected frictionally to the member 118 and its plate 134, so that this member is driven by the sprocket wheel and acts through the connections described to rotate the shaft 12.

For imparting the above-described clutch-setting movement to the arm 144, the front end of this arm is connected by a link 156 to a bar 158 vertically movable in the previously mentioned bracket 8, this bar being normally held up by a spring 160 in a position determined by engagement of a pin 162 on the bar with the lower face of the bracket 8. Also vertically movable in the bracket 8 is a bar 164 the lower end of which is arranged to engage the upper end of a screw 166 threaded in a lug on the bar 158. Pivottally connected to the bar 164 is a rod 168 adjustably connected by a coupling 170 to another rod 172 the lower end of which extends downwardly through an opening in an arm 174 fast on the treadle 90. Below the arm 174 a collar 176 is fast on the rod 172, this collar being normally spaced far enough below the arm to permit the gripper jaw 32 to be closed on the upper by depression of the treadle, as hereinbefore described, before the treadle acts on the clutch. It will be understood that in response to the depression of the treadle the bar 158 is moved downwardly against the resistance of the spring 160 by the engagement of the bar 164 with the screw 166, and that upward movement of the bar 158 to release the clutch and stop the machine is effected by the spring 160. To maintain the clutch in operating condition after the operator releases the treadle 90 the shaft 12 carries means for holding the bar 164 depressed. This means comprises a cup-like member 178 which is coupled to the sprocket wheel 100 fast on the shaft and is arranged for peripheral engagement with the upper end of the bar 164 to hold the bar depressed after it has been depressed by the treadle. A portion of the member 178 is broken away to provide a recess 180 into which the bar 164 is forced upwardly by the spring 160 as the shaft 12 approaches the end of one revolution. It will be understood that when the bar is thus forced upwardly into the recess 180 the clutch is released to disconnect the shaft 12 from the source of power, and the shaft is stopped in the right position by the engagement of a face 182 on the member 178 with the bar 164, as illustrated in Fig. 1.

The shoe rest 28 on which the shoe is supported as hereinbefore described is fast on the upper end of a bar 182 vertically movable in a bracket 184 fast on the head 4. Springs 186 connected at their upper ends to pins on the bracket 184 and at their lower ends to a collar 188 fast on the bar 182 tend to move the bar upwardly and hold it initially in a position determined by engagement of a collar 190 fast thereon with the lower end of the bracket 184. When

the operator places a shoe on the shoe rest 28 he may, therefore, move the shoe rest downwardly against the resistance of the springs 186 until the upper side of the shoe is in proper relation to the gripper. Immediately after the starting of the power operation of the machine the shoe rest is locked against any further downward movement. For this purpose there is provided a pin 192 which lies in a recess in the bracket 184 and the opposite ends of which are supported by shoulders formed on arms 194 arranged respectively at opposite sides of the bracket 184 and fast on a shaft 196 rotatable in the bracket. A spring 198 mounted in a socket in the bracket bears downwardly on the pin 192 and tends to wedge the pin between the vertical rear face of the bar 182 and an inclined face on a hardened plate 200 on the bracket. It will be understood that when the pin is in this position it locks the bar 182 and the shoe rest thereon against downward movement. Initially, however, the pin is held upraised by the arms 194 to release the bar and permit its downward movement. For this purpose there is fast on the shaft 196 an arm 202 connected by a link 204 to the lower end of a lever 206 pivotally mounted on a pin 208 on the bracket 8. At its upper end the lever carries a roll 210 engaged by a cam 212 on the member 178 to hold the arms 194 initially in positions to release the bar 182. Immediately after the starting of the power operation of the machine the cam 212 passes beyond the roll 210 and permits the lever 206 to be swung by a spring 214 in the direction to lower the arms 194, so that the pin 192 is forced downward by the spring 198 into position to lock the bar 182 against further downward movement. Near the end of the cycle of operations the cam 212 acts on the roll 210 to swing the lever 206 reversely and thus to lift the pin 192 from its locking position.

After the starting of the power operation of the machine, the first operation performed on the work is a movement of the last heightwise in a forward direction to cause the upper to be pulled by the gripper which is held closed by the treadle. For this purpose there is provided on the gripper, in front of the lower jaws 30, a plate 216 (Figs. 3 and 4) arranged to engage the insole and to act as a pusher to impart forward movement to the last, or at least to the upper side portion of the last the lower side of which rests on the shoe rest 28, while also pressing the insole close against the bottom of the last. The plate 216 has a stem 218 extending rearwardly therefrom in a socket formed in the middle jaw 30 and its arm 34 and provided with a pin 220 extending laterally through slots 222 in the arm. This pin is provided on its ends with rolls 224 which lie in slots formed in arms 226 extending upwardly between the middle gripper jaw arm 34 and the arms 34 adjacent thereto. The arms 226 are fast at their lower ends on a shaft 228 rotatably mounted in the yoke member 38 which carries the gripper jaws 30, and also fast on this shaft is a rearwardly extending arm 232. A roll 234 carried by the segmental member 16 is arranged to engage the rear-end portion of the arm 232 substantially at the beginning of the power operation of the machine and by swinging this arm to impart the required forward movement to the plate 216, as illustrated in Fig. 6. To render the roll thus effective on the arm 232 it is necessary to prevent the yoke member 38 from turning with the member 16 at the beginning of the movement of the latter. For this pur-

pose the yoke member has a rearwardly extending arm 236 the rear end of which is arranged to be engaged above by a latch 238 fast on a block 239 pivotally mounted by means of a pin 240 (Fig. 2) on a plate 242 secured on the head 4. The latch 238 is controlled by a spring 244 connected at its front end to an arm 246 extending downwardly from the block 239 and connected at its rear end to a rod 248 movable lengthwise in an opening in a bracket 250 fast on the head 4. A hand wheel 252 threaded on the rod 248 and engaging the bracket 250 serves by movement of the rod to adjust the tension of the spring 244, and the rod 248 may be locked in adjusted position by another hand wheel 254 threaded thereon and arranged to engage the bracket on the opposite side from the wheel 252. Movement of the latch 238 by the spring 244 is limited by engagement of the block 239 with a stop 255 on the head 4. It will be evident that as the segmental member 16 turns relatively to the yoke member 38 to cause the plate 216 to act on the last, the end face 20 of the rim 18 approaches the arms 54 which carry the gripper jaw 32. This end of the rim then engages the arms 54, as illustrated in Fig. 6, and as the member 16 continues its movement it acts on the gripper to force it downwardly in the direction to pull the margin of the upper inwardly over the insole. Shortly after the downward movement of the gripper begins, however, the force applied through the gripper and the springs 44 to the yoke member 38 causes the arm 236 of this member to slip past the latch 238. This permits the spring 52 quickly to turn the yoke member in a counterclockwise direction about the shaft 12 until it is stopped by engagement with the edge face 50 of the segmental member 16. As a result of this movement of the yoke member the arm 232 is released by the roll 234, thus permitting the plate 216 to be returned to its initial position relatively to the jaws 30 by a spring 256 connected to the pin 36 and to the hub of the arm 232, and the jaws 30 are also moved away from the jaw 32 to release the margin of the upper, the plate 216 moving with the jaws 30 about the axis of the shaft 12. By reason of the fact that the operator, in controlling the shoe, applies to it force tending to move it in a rearward direction, it moves or tips instantly in that direction as soon as permitted by the release of the plate 216, so that the margin of the upper is pressed against the insole by a wiper plate 258 (Fig. 7) which is carried by the rim 18 and, as illustrated in Fig. 6, actually arrives in position to engage the upper before its margin is released by the gripper. This wiper plate or wiper 258, as illustrated in Fig. 2, has a scalloped or serrated upper-engaging edge 260, so that it tends to regulate the formation of wrinkles in the margin of the upper as it wipes it inwardly over the insole in the continued turning movement of the segmental member 16. It will be understood that just after the release of the upper by the gripper the jaw 32 is returned to its initial position relatively to the member 16 by the spring 66 (Fig. 3) which was tensioned as the member 16 moved relatively to the gripper to bring the end face 20 of the rim 18 into contact with the arms 54, the projection 74 being carried away from the latch 72 since the downward movement of the latch-supporting bar 78 is limited by engagement of a shoulder 262 (Fig. 1) thereon with a plate 263 on the front of the bracket 80. Beyond the smooth wiper 258 the rim 18 is corrugated to provide teeth 264 which dur-

ing continued rotation of the member 16 act with greater force on the margin of the upper to wipe it tightly and smoothly over the insole. While the teeth 264 are thus acting on the upper 5 the operator may tip the shoe in any direction desired to produce the best wiping and smoothing effect on all portions of the margin acted upon by the rim 18, the member 16 being turned slowly enough to render it practicable for the 10 shoe to be manipulated and treated in this manner.

While the functions of the various parts have been explained in considerable detail in the foregoing description, the manner of operation of the 15 machine as a whole will now be briefly summarized. A shoe to be operated upon by the machine constructed as described will preferably have been already lasted at its toe-end portion and along its shank portion before it comes to the machine, and before the shoe is presented to the machine a suitable cement will have been applied to the margin of the insole and between the layers of the upper materials along the ball portion of the shoe. The operator presents the 20 shoe with one side thereof supported on the shoe rest 28 and with the unlasted margin of the upper materials along the other side of the ball portion of the shoe between the jaws of the gripper, as illustrated in Fig. 3, the insole near its upper edge being engaged by the plate 216. In thus presenting the shoe the operator may force the shoe rest 28 downwardly against the resistance of the springs 186 by pressure of the shoe thereon until the upper side of the shoe is in proper relation to the gripper. After thus presenting the shoe the operator depresses the treadle 90 to swing the gripper jaw 32 downwardly into position to grip the upper against the jaws 30 through the action of the latch 72 on the projection 74, 25 as illustrated in Fig. 5. Further depression of the treadle serves first to tension the springs 96 through which the jaw 32 is maintained yieldingly in its upper-gripping position, and then, by the action of the treadle arm 174 on the rod 172, to 30 lower the bars 158 and 164 and thus start the power operation of the machine. Immediately after the starting of the machine the member 178 passes over the upper end face of the bar 164 to maintain the clutch in operating condition 35 independently of the treadle, but the operator continues to hold the treadle depressed to maintain the grip on the upper until after the pull has been applied to the upper. Just after the starting of the machine also the cam 212 passes 40 beyond the roll 210, so that the shoe rest 28 is locked against further downward movement by the pin 192 in response to the action of the spring 214 on the lever 206.

As the segmental member 16 begins to turn, 45 the yoke member 38 is held from turning by the action of the latch 238 on the arm 236, so that the roll 234 on the member 16 acts on the arm 232 to force the plate 216 forwardly and thus to impart to the last or to the upper portion thereof a heightwise movement relatively to the gripper to cause the gripper to pull the upper while the gripper remains stationary, as illustrated in Fig. 6. As this pull is completed the end face 20 of the rim 18 arrives in position 50 to engage the arms 54 which carry the jaw 32 of the gripper, and by this engagement the gripper and the yoke member 38 are then forced to turn with the member 16 until the arm 236 on the yoke member slips past the spring-controlled latch 239. The margin of the upper is thus

pulled inwardly over the insole by the gripper. Immediately upon the release of the yoke member 38 by the latch 238 the spring 52 returns the yoke member to its normal position relatively to the segmental member 16. In response to such movement of the yoke member by the spring 52 the shoe-engaging plate 216 is released to permit a quick rearward movement of the shoe by the force which the operator is applying to it, and the gripper is opened to release the margin of the upper which is caught between the insole and the downwardly moving wiper 258, as illustrated in Fig. 7. The wiper wipes the upper inwardly over the insole, and as the rim 18 continues to turn its teeth 264 arrive in position to 10 contact on the upper, as illustrated in Fig. 8, to wipe and press its margin against the insole with greater force. Since these teeth extend throughout the greater portion of the length of the rim 18, the operator is afforded opportunity to tip the shoe in any direction desired while pressing it inwardly against the teeth to cause them to act on different portions of the margin of the upper in the manner required for the best results in wiping it smoothly over the insole. Near the end 15 of the cycle of operations the cam 212 acts on the lever 206 to unlock the shoe rest, and immediately thereafter the recess 180 in the member 178 arrives opposite the upper end of the bar 164, permitting the spring 160 to move this bar 20 and the bar 158 upwardly to release the clutch, the shaft 12 and the parts thereon being stopped in the right position by engagement of the bar 164 with the face 182 of the member 178. The operator then turns the shoe over and proceeds 25 in the same manner as before to cause the machine to last the other side of the shoe along the ball portion.

In the modification shown in Figs. 9, 10 and 11 there are substituted for the single gripper jaw 32 of the first-described construction three jaws 266 formed on arms 268 spaced from one another lengthwise of the edge of the shoe bottom, as illustrated in Fig. 10. In this construction the two arms 40 of the yoke member 38 are next to the segmental member 16, instead of being spaced therefrom as in the first-described construction, and the two outside gripper jaw arms 268 have offset hub portions 270 mounted to turn on the shaft 12 in spaced relation to the 30 arms 40. A pin 272 extends through the three arms 268 and thereby connects these three arms for movement in unison about the shaft 12, this pin being fastened to the middle arm and provided with an angularly shaped end 274 arranged to be engaged by the latch 72 for closing the jaws 266 on the upper in the same manner as the jaw 32 of the first-described construction. A key 276 in the pin 272 connects the middle arm 268 to the right-hand arm so as to prevent 35 any swinging movement of the middle arm relatively to the other two arms. The two outside arms 268 are not only mounted to turn on the shaft 12 but are also movable along the shaft and along the pin 272 toward or from each other to carry the outside jaws 266 toward or from the middle jaw. Between the hub portions 270 of the outside arms 268 and the arms 40 of the yoke member 38 are springs 278, and mounted also on the pin 272 between the middle 40 arm 268 and the outside arms are springs 280. The springs 278 and 280 accordingly tend to move the outside arms outwardly away from each other. Mounted on the shaft 12 in engagement with the outer faces of the hub portions 45

270 are cam members 282 which are movable along the shaft 12 but are connected to the shaft to turn therewith by keys 284. These cam members are provided with cam faces 286 engaged by stationary pins 288 mounted in the previously mentioned brackets 8 and 10. These pins accordingly act, in response to turning movement of the shaft 12, to move the cam members 282 and the outside gripper jaw arms 268 inwardly toward each other against the resistance of the springs 278 and 280, the result being that the two outside gripper jaws 266, by their movements toward the middle jaw, have a gathering effect on the margin of the upper to insure regularity in the gathering or wrinkling of the margin along the convexly curved edge of the ball portion of the shoe bottom. It will be evident that this gathering of the margin of the upper begins substantially as soon as the shaft 12 starts to turn, and it continues while the last is being moved heightwise relatively to the gripper by the member 216 to cause the gripper to pull the upper in the manner hereinbefore explained. Cooperating with the jaws 266 to grip the margin of the upper are three lower jaws 290 (Fig. 11) formed on arms 292 which are pivotally mounted on the pin 36 in the same manner as the arms 34 of the first-described construction, except that the two outside arms 292 are located normally farther from the middle arm than are the outside arms 34, and between the outside arms and the middle arm there are mounted on the pin 36 comparatively light springs 294 against the resistance of which the outside arms may approach the middle arm in response to the frictional drag of the margin of the upper on the outside jaws 290 as the corresponding outside jaws 266 are forced inwardly in the manner above described. Instead of the 50 springs 44 of the first-described construction, there are provided springs 296 mounted in sockets in the arms 292 and controlling plungers 298 which bear on the yoke member 38, thus facilitating the required movements of the outside arms 292. In other respects the modified construction shown in Figs. 9, 10 and 11 is substantially the same as the first-described construction, as are also the operations performed in the lasting of the shoe.

Having described the invention, what I claim as new and desire to secure by Letters Patent of the United States is:

1. In a lasting machine, a rotary lasting device comprising gripper jaws for gripping the margin of an upper on a last between them and for pulling the upper and comprising also means for laying the margin of the upper inwardly over the bottom of the last as the device is rotated, and means for rotating said device completely about its axis in operating it.

2. In a lasting machine, a rotary lasting device comprising a gripper for gripping the margin of an upper on a last and for pulling the upper and comprising also means for laying the margin of the upper inwardly over the bottom of the last as the device is rotated, power-operated means for rotating said device, and automatic means for bringing the device to a stop at the end of each complete rotation about its axis.

3. In a lasting machine, a rotary lasting device of generally circular form having at its periphery means for wiping the margin of an upper inwardly over an insole on a last as the device is rotated, said device including also mem-

bers for gripping the margin of the upper between them and for pulling the upper before its margin is thus wiped inwardly, and means for rotating said device to operate it.

4. In a lasting machine, a rotary lasting device comprising a segmental member curved in an arc part way around the axis of the device for wiping the margin of an upper inwardly over an insole on a last as the device is rotated and comprising also a gripper normally spaced about 10 said axis from said segmental member for gripping the margin of the upper and pulling the upper, and means for rotating said member and gripper completely about said axis in the lasting operation.

5. In a lasting machine, a rotary lasting device comprising a segmental member curved in an arc part way around the axis of the device for wiping the margin of an upper inwardly over an insole on a last as the device is rotated and comprising also a gripper for gripping the margin of the upper and pulling the upper, said member and gripper being relatively movable about said axis, and means for rotating both said member and gripper about said axis in the lasting operation.

6. In a lasting machine, a rotary lasting device comprising a segmental member curved in an arc more than half way around the axis of the device for wiping the margin of an upper 30 inwardly over an insole on a last as the device is rotated and comprising also means for gripping the margin of the upper in the space between the opposite ends of said segmental member and for pulling the upper, and means for rotating said member and the upper-gripping and pulling means about said axis in the lasting operation.

7. In a lasting machine, a rotary lasting device having smooth wiping means for wiping the 40 margin of an upper inwardly over an insole on a last and provided beyond said smooth wiping means with a series of teeth for continuing the wiping action on the margin of the upper as the device is rotated, said rotary device including also means for gripping the margin of the upper and for pulling the upper before its margin is thus wiped inwardly.

8. In a lasting machine, a device movable to wipe the margin of an upper inwardly over an insole on a last, said device having a smooth portion for first wiping the margin inwardly and being provided beyond said smooth portion with a series of teeth for continuing the wiping action on the margin during further movement of the device.

9. In a lasting machine, a rotary lasting device comprising gripper jaws for gripping the margin of an upper on a last between them and for pulling the upper inwardly over an insole on the last as the device is rotated and comprising also means for wiping the margin of the upper inwardly over the insole by further rotation of the device, and means for rotating said device completely about its axis in operating it.

10. In a lasting machine, a lasting device rotatable about an axis in the lasting operation and having a wiper curved about said axis for wiping the margin of an upper inwardly over an insole on a last as the device is rotated, said device including also gripper jaws for gripping the margin of the upper between them and for pulling the upper inwardly over the insole by the rotation of the device.

11. In a power-operated lasting machine, a 75

rotary lasting device comprising a gripper for gripping the margin of an upper on a last and for pulling the upper and comprising also means for laying the margin of the upper inwardly over an insole on the last as the device is rotated, power-operated means for rotating said device, and means for closing the gripper on the upper and for thereafter starting the power operation of the machine.

12. In a power-operated lasting machine, a rotary lasting device comprising a gripper for gripping the margin of an upper on a last and for pulling the upper and comprising also means for laying the margin of the upper inwardly over an insole on the last as the device is rotated, power-operated means for rotating said device, means movable by the operator to close the gripper on the upper, and means for starting the power operation of the machine while the gripper is held closed by the operator.

13. In a power-operated lasting machine, a rotary lasting device comprising a gripper for gripping the margin of an upper on a last and for pulling the upper and comprising also means for laying the margin of the upper inwardly over an insole on the last as the device is rotated, power-operated means for rotating said device, a member movable by the operator to close the gripper on the upper, and means for starting the power operation of the machine by further movement of said member after the closing of the gripper.

14. In a power-operated lasting machine, a rotary lasting device comprising a gripper for gripping the margin of an upper on a last and for pulling the upper and comprising also means for laying the margin of the upper inwardly over an insole on the last as the device is rotated, power-operated means for rotating said device, a member movable by the operator to close the gripper on the upper and further movable thereafter to start the power operation of the machine, and a spring arranged to be subjected to stress by the further movement of said member to hold the gripper yieldingly closed.

15. In a lasting machine, a gripper for gripping the margin of an upper on a last and for pulling the upper, means movable by the operator to close said gripper on the upper, and mechanism movable relatively to the gripper into position to act thereon while it is held closed by the operator and further movable thereafter to force the gripper inwardly over the bottom of the last.

16. In a lasting machine, a gripper comprising a pair of jaws for gripping the margin of an upper on a last and for pulling the upper, means movable by the operator to move one of said jaws toward the other to grip the upper, and mechanism movable into position to act on said first-named jaw while it is held in gripping relation to the upper by the operator and further movable thereafter to force the pair of jaws inwardly over the bottom of the last.

17. In a lasting machine, a gripper for gripping the margin of an upper on a last and for pulling the upper, means for laying the margin of the upper inwardly over an insole on the last, and mechanism movable by the operator to close said gripper on the upper, said overlaying means being movable relatively to the gripper toward the margin of the upper while the gripper is held closed by the operator and being arranged by continued movement thereafter to force the gripper inwardly over the insole.

18. In a lasting machine, a gripper for gripping

the margin of an upper on a last and for pulling the upper, means for laying the margin of the upper inwardly over an insole on the last, and mechanism movable by the operator to close said gripper on the upper, said overlaying means being movable relatively to the gripper into engagement therewith while the gripper is held closed by the operator and being thereafter further movable to force the gripper inwardly over the insole and to lay the margin of the upper over the insole.

19. In a lasting machine, a gripper for gripping the margin of an upper on a last and for pulling the upper, means for laying the margin of the upper inwardly over an insole on the last, said gripper and overlaying means being both movable about a common axis, and mechanism for moving said overlaying means relatively to the gripper about said axis toward the margin of the upper and for thereafter moving the gripper about said axis inwardly over the insole by further movement of said overlaying means.

20. In a lasting machine, a gripper for gripping the margin of an upper on a last and for pulling the upper, means for laying the margin of the upper inwardly over an insole on the last, said gripper and overlaying means being both movable about a common axis, mechanism movable by the operator to close the gripper on the upper, and power-operated mechanism for moving said overlaying means relatively to the gripper about said axis toward the margin of the upper while the gripper is held closed by the operator and for thereafter forcing the gripper inwardly over the insole by further movement of said overlaying means.

21. In a lasting machine, a gripper for gripping the margin of an upper on a last and for pulling the upper, said gripper being mounted for swinging movement inwardly over an insole on the last, a wiper for wiping the margin of the upper inwardly over the insole, and a member supporting said wiper and movable about the same axis as the gripper to carry the wiper toward the margin of the upper, said member being movable relatively to the gripper about said axis after the gripper has gripped the margin of the upper and being arranged to force the gripper thereafter inwardly over the insole by continued movement about said axis.

22. In a lasting machine, a gripper for gripping the margin of an upper on a last and for pulling the upper, means for laying the margin of the upper inwardly over an insole on the last, said overlaying means being movable relatively to the gripper toward the margin of the upper while the gripper is gripping the upper and being arranged by continued movement thereafter to force the gripper inwardly over the insole, and a device for holding the gripper against movement inwardly over the insole while said overlaying means is moving relatively thereto, said device being arranged to release the gripper thereafter in response to the force applied to the gripper by said overlaying means.

23. In a lasting machine, a gripper for gripping the margin of an upper on a last and for pulling the upper, said gripper being mounted for swinging movement inwardly over an insole on the last, a wiper for wiping the margin of the upper inwardly over the insole, a member supporting said wiper and movable about the same axis as the gripper to carry the wiper toward the margin of the upper, said member being first movable relatively to the gripper about said axis and being arranged by continued movement thereafter to

force the gripper inwardly over the insole, and a device for holding the gripper against movement about said axis while said member is moving relatively thereto, said device being arranged to release the gripper thereafter in response to the force applied to the gripper by said member.

24. In a lasting machine, a gripper for gripping the margin of an upper on a last and for pulling the upper, said gripper being mounted for swinging movement inwardly over an insole on the last, mechanism movable by the operator to close said gripper on the upper, a wiper for wiping the margin of the upper inwardly over the insole, a member supporting said wiper and movable about the same axis as the gripper to carry the wiper toward the margin of the upper, said member being movable relatively to the gripper about said axis while the gripper is held closed by the operator and being arranged by continued movement thereafter to force the gripper inwardly over the insole, and a device for yieldingly holding the gripper against movement about said axis while said member is moving relatively thereto, said device being arranged to release the gripper thereafter in response to the force applied to the gripper by said member.

25. In a lasting machine, a rotary lasting device comprising a segmental member curved in an arc part way around the axis of the device for wiping the margin of an upper inwardly over an insole on a last as the device is rotated and comprising also a gripper for gripping the margin of the upper and pulling the upper, and means for moving said segmental member first relatively to the gripper about said axis and for thereafter forcing the gripper also to move about said axis by the action of said segmental member thereon.

26. In a lasting machine, a rotary lasting device comprising a segmental member curved in an arc part way around the axis of the device for wiping the margin of an upper inwardly over an insole on a last as the device is rotated and comprising also a gripper for gripping the margin of the upper and pulling the upper, means for moving said segmental member first relatively to the gripper about said axis and for thereafter forcing the gripper also to move about said axis, and a device for yieldingly holding the gripper against such movement while the segmental member moves relatively thereto and for then releasing the gripper in response to the force applied thereto.

27. In a lasting machine, a gripper for gripping the margin of an upper on a last and for pulling the upper, means for laying the margin of the upper inwardly over an insole on the last, said overlaying means being movable relatively to the gripper toward the margin of the upper while the gripper is gripping the upper and being arranged by continued movement thereafter to force the gripper inwardly over the insole, a device for holding the gripper against movement inwardly over the insole while said overlaying means is moving relatively thereto, said device being arranged to release the gripper thereafter in response to the force applied to the gripper by the overlaying means, and means for automatically opening the gripper upon its release by said device.

28. In a lasting machine, a gripper for gripping the margin of an upper on a last and for pulling the upper, said gripper being mounted for swinging movement inwardly over an insole on the last, a wiper for wiping the margin of the upper inwardly over the insole, a member supporting said

wiper and movable about the same axis as the gripper to carry the wiper toward the margin of the upper, said member being movable relatively to the gripper about said axis after the gripper has gripped the upper and being arranged to force the gripper thereafter inwardly over the insole by continued movement about said axis, a device for holding the gripper against movement inwardly over the insole while said member is moving relatively thereto and for thereafter releasing the gripper in response to the force applied to the gripper by said member, and spring means for swinging the gripper relatively to said member about said axis and for opening it upon its release by said device.

29. In a lasting machine, a gripper for gripping the margin of an upper on a last and for pulling the upper, said gripper being mounted for swinging movement inwardly over an insole on the last, means movable by the operator to close the gripper on the upper, a wiper for wiping the margin of the upper inwardly over the insole, a member supporting said wiper and movable about the same axis as the gripper to carry the wiper toward the margin of the upper, said member being movable relatively to the gripper about said axis while the gripper is held closed by the operator and being arranged to force the gripper thereafter inwardly over the insole by continued movement about said axis, a device for holding the gripper against movement inwardly over the insole while said member is moving relatively thereto and for thereafter releasing the gripper in response to the force applied to the gripper by said member, and spring means for swinging the gripper relatively to said member about said axis and for opening it upon its release by said device.

30. In a power-operated lasting machine, a gripper for gripping the margin of an upper on a last, power-operated means for effecting relative movement of the gripper and the last in a direction heightwise of the last to cause the gripper to pull the upper, means movable by the operator to close the gripper on the upper, and means for starting the power operation of the machine while the gripper is held closed by the operator.

31. In a power-operated lasting machine, a gripper for gripping the margin of an upper on a last, power-operated means for effecting relative movement of the gripper and the last to cause the gripper to pull the upper, a member movable by the operator to close the gripper on the upper, and means for starting the power operation of the machine by further movement of said member after the closing of the gripper.

32. In a power-operated lasting machine, a gripper for gripping the margin of an upper on a last, means movable by the operator to close the gripper on the upper prior to the starting of the power operation of the machine, and power-operated means for moving the last heightwise relatively to the gripper to cause the gripper to pull the upper while it is held closed by the operator.

33. In a lasting machine, a gripper for gripping the margin of an upper on a last, means for laying the margin of the upper inwardly over an insole on the last, said overlaying means being movable relatively to the gripper toward the margin of the upper and being thereafter further movable to lay the upper over the insole, and means for moving the last heightwise relatively to the gripper to cause the gripper to pull the upper as the overlaying means thus moves relatively to the gripper.

34. In a lasting machine, a gripper for gripping

the margin of an upper on a last, means for laying the margin of the upper inwardly over an insole on the last, said overlaying means being movable relatively to the gripper toward the margin of the upper and being thereafter further movable to lay the upper over the insole, and a member for engaging the insole and moving the last heightwise relatively to the gripper to cause the gripper to pull the upper as the overlaying means thus moves relatively to the gripper, said member and the gripper being thereafter movable inwardly over the insole with the overlaying means.

35. In a lasting machine, a gripper for gripping the margin of an upper on a last, means for laying the margin of the upper inwardly over an insole on the last, said overlaying means being movable relatively to the gripper toward the margin of the upper and being thereafter further movable to lay the upper over the insole, an insole-engaging member, and means for operating said member to move the last heightwise relatively to the gripper and thus cause the gripper to pull the upper as the overlaying means moves relatively to the gripper and for then releasing said member to permit reverse heightwise movement of the last substantially as soon as said overlaying means arrives in position to operate on the upper.

36. In a lasting machine, a gripper for gripping the margin of an upper on a last controlled with respect to movement in a heightwise direction by the operator, means for laying the margin of the upper inwardly over an insole on the last, said overlaying means being movable relatively to the gripper toward the margin of the upper and being thereafter further movable to lay the upper over the insole, an insole-engaging member, and means for operating said member to move the last heightwise relatively to the gripper and thus cause the gripper to pull the upper as the overlaying means moves relatively to the gripper and for then releasing said member to permit the last to be moved reversely heightwise by the operator into position to render the overlaying means effective to press the margin of the upper on the insole.

37. In a lasting machine, a gripper for gripping the margin of an upper at one side of a last controlled with respect to movement in a heightwise direction by the operator, a shoe rest for engaging the upper at the other side of the last to hold the last against movement in a widthwise direction, means movable to lay the margin of the upper engaged by said gripper inwardly over an insole on the last, an insole-engaging member, and means for operating said member to move the last heightwise relatively to the gripper and thus cause the gripper to pull the upper and for then releasing said member to permit the operator to move the last reversely in a heightwise direction into position to render the overlaying means effective to press the margin of the upper on the insole.

38. In a lasting machine, a rotary lasting device comprising a gripper for gripping the margin of an upper on a last and for pulling the upper and comprising also means for laying the margin of the upper inwardly over the bottom of the last as the device is rotated, said rotary device being further provided with means for moving the last heightwise relatively to the gripper by pressure on the bottom of the last to cause the gripper to pull the upper before its

margin is thus laid inwardly by said overlaying means.

39. In a lasting machine, a rotary lasting device comprising a gripper for gripping the margin of an upper on a last and for pulling the upper and comprising also means for laying the margin of the upper inwardly over the bottom of the last as the device is rotated, said rotary device being further provided with means for moving the last heightwise relatively to the gripper by pressure on the bottom of the last to cause the gripper to pull the upper, and means for holding the gripper substantially stationary at the beginning of the rotation of other portions of said device until a pull has thus been applied to the upper.

40. In a lasting machine, a rotary lasting device comprising a gripper for gripping the margin of an upper on a last and for pulling the upper and comprising also means for laying the margin of the upper inwardly over an insole on the last as the device is rotated, said rotary device being further provided with a member for engaging the insole and moving the last heightwise relatively to the gripper to cause the gripper to pull the upper, and means for thus operating said member in response to the rotation of a portion of said device.

41. In a lasting machine, a rotary lasting device comprising a gripper for gripping the margin of an upper on a last and for pulling the upper and comprising also means for laying the margin of the upper inwardly over an insole on the last as the device is rotated, said rotary device being further provided with a member for engaging the insole and moving the last heightwise relatively to the gripper to cause the gripper to pull the upper, means for thus operating said member in response to the rotation of a portion of said device, and mechanism for holding said member and the gripper against rotation about the axis of said device until a pull has thus been applied to the upper and for then releasing them to permit them to rotate with the rest of said device.

42. In a lasting machine, a rotary lasting device comprising a gripper for gripping the margin of an upper on a last and for pulling the upper and comprising also means for laying the margin of the upper inwardly over an insole on the last as the device is rotated, said rotary device being further provided with a member for engaging the insole and moving the last heightwise relatively to the gripper to cause the gripper to pull the upper, and means for thus operating said member and for then releasing it to permit reverse heightwise movement of the last into position to render the overlaying means effective to press the margin of the upper on the insole.

43. In a lasting machine, a rotary lasting device arranged to operate on an upper at one side of a last controlled with respect to movement in a heightwise direction by the operator, a shoe rest for engaging the upper at the other side of the last to hold the last against movement in a widthwise direction, said rotary lasting device comprising a gripper for gripping the margin of the upper and comprising also means for laying the margin of the upper inwardly over an insole on the last as the device is rotated, said device being further provided with a member for engaging the insole and moving the last heightwise relatively to the gripper to cause the gripper to pull the upper, and means for thus operating said member and for then releasing it to permit re-

verse heightwise movement of the last by the operator into position to render the overlaying means effective to press the margin of the upper on the insole.

5 44. In a lasting machine, a segmental member rotatable to wipe the margin of an upper inwardly over an insole on a last, a gripper for gripping the margin of the upper, said gripper being mounted to rotate about the same axis as said member, an insole-engaging member rotatable with said gripper and movable also in a direction away from said axis to move the last heightwise relatively to the gripper and thus cause the gripper to pull the upper, mechanism for thus operating said insole-engaging member by rotation of said segmental member relatively to the gripper, and a device for holding the gripper and said insole-engaging member against rotation until after a pull has been applied by the gripper to the upper and for then releasing them to permit them to rotate with the segmental member.

25 45. In a lasting machine, a segmental member rotatable to wipe the margin of an upper inwardly over an insole on a last, a gripper for gripping the margin of the upper, said gripper being mounted to rotate about the same axis as said member, an insole-engaging member rotatable with said gripper and movable also in a direction away from said axis to move the last heightwise relatively to the gripper and thus cause the gripper to pull the upper, mechanism for thus operating said insole-engaging member by rotation of said segmental member relatively to the gripper, and a device for holding the gripper and said insole-engaging member against rotation until after a pull has been applied by the gripper to the upper and for then releasing them to permit them to rotate with the segmental member, said insole-engaging member being reversely movable toward said axis upon its release by said device to permit reverse heightwise movement of the last toward the segmental member.

40 46. In a lasting machine, a gripper for gripping the margin of an upper along the side of the ball portion of a last and for pulling the upper, said gripper comprising jaws having upper-gripping faces curved lengthwise of the edge of the upper similarly to the curvature of the edge of the 50 last bottom along the ball portion and movable to pull the upper inwardly over an insole on the last, and a wiper for wiping the margin of the upper engaged by said gripper inwardly over the insole, said wiper having a serrated edge 55 for engaging the upper to regulate the formation of wrinkles in its margin.

47. In a lasting machine, a plurality of pairs of upper-gripping jaws arranged to grip the margin of an upper on a last in different locations respectively along the edge of the upper, means for effecting relative movement of said jaws and the last to pull the upper, and additional means for moving said pairs of jaws toward each other in directions lengthwise of the edge of the upper to gather the margin of the upper.

60 48. In a lasting machine, a plurality of pairs of upper-gripping jaws arranged to grip the margin of an upper on a last in different locations respectively along the edge of the upper, means for effecting relative movement of said jaws and the last to pull the upper, mechanism for also effecting relative movement of said pairs of jaws to gather the margin of the upper located between them, and spring means tending to separate said pairs of jaws and against the resistance

of which such relative movement of the different pairs is effected.

49. In a lasting machine, upper-gripping means for gripping the margin of an upper on a last, said upper-gripping means comprising a middle pair of upper-gripping jaws and other pairs of jaws located respectively at opposite sides of said middle pair, means for effecting relative movement of said jaws and the last to pull the upper, and additional means for also moving said other pairs of jaws toward the middle pair to gather the margin of the upper.

50. In a lasting machine, a rotary lasting device comprising upper-gripping means for gripping the margin of an upper on a last and for pulling the upper and also comprising means for laying the margin of the upper inwardly over an insole on the last as the device is rotated, said upper-gripping means comprising a plurality of pairs of upper-gripping jaws arranged to grip the margin of the upper respectively in different locations along the edge of the upper, and means for effecting relative movement of said different pairs of jaws lengthwise of the axis of said device to gather the margin of the upper between them before said margin is laid over the insole by said overlaying means.

51. In a lasting machine, a rotary lasting device comprising upper-gripping means for gripping the margin of an upper on a last and for pulling the upper and also comprising means for laying the margin of the upper inwardly over an insole on the last as the device is rotated, said upper-gripping means comprising a plurality of pairs of upper-gripping jaws arranged to grip the margin of the upper respectively in different locations along the edge of the upper, a shaft on which said device is mounted, said shaft being rotatable to move said overlaying means toward the pairs of jaws prior to the laying of the margin of the upper over the insole, and mechanism for effecting relative movement of said pairs of jaws lengthwise of the axis of said shaft to gather the margin of the upper in response to the rotation of the shaft as the overlaying means thus approaches the jaws.

52. In a lasting machine, a rotary lasting device comprising upper-gripping means for gripping the margin of an upper on a last and for pulling the upper and also comprising means for laying the margin of the upper inwardly over an insole on the last as the device is rotated, said upper-gripping means comprising a middle pair of upper-gripping jaws and other pairs of jaws at opposite sides of said middle pair for gripping the margin of the upper respectively in different locations along the edge of the upper, a shaft on which said device is mounted, and cam means for moving said other pairs of jaws toward the middle pair lengthwise of the axis of said shaft to gather the margin of the upper in response to rotation of the shaft before the overlaying means arrives in position to lay the margin of the upper over the insole.

53. In a lasting machine, a rotary lasting device comprising upper-gripping means for gripping the margin of an upper on a last and for pulling the upper and also comprising means for laying the margin of the upper inwardly over an insole on the last as the device is rotated, said upper-gripping means comprising a plurality of pairs of upper-gripping jaws arranged to grip the margin of the upper respectively in different locations along the edge of the upper, a rotatable shaft on which said device is mounted, means

for holding said pairs of jaws against rotation with said shaft at the beginning of such rotation, and means for effecting relative movement of said jaws and the last heightwise of the last to cause the jaws to pull the upper and for also effecting relative movement of the different pairs of jaws lengthwise of the axis of the shaft to gather the margin of the upper in response to rotation of the shaft while said jaws are thus held from rotating.

54. In a lasting machine, a rotary lasting device having means for gripping the margin of an upper at one side of a last and for pulling the upper and also means for laying the margin of the upper inwardly over the bottom of the last as the device is rotated, means for rotating said device completely about its axis in operating it, and a work rest arranged to engage the upper at the other side of the last to support the last against movement in a widthwise direction as the upper is thus operated upon.

55. In a lasting machine, a lasting device arranged to operate on a shoe controlled with respect to movement in a heightwise direction by the hands of the operator, said device comprising a gripper for gripping the margin of the upper at one side of the shoe and for pulling the upper and a wiper for thereafter wiping the margin of the upper inwardly over an insole, the gripper and the wiper being both movable inwardly over the insole simultaneously, and means for engaging the upper at the other side of the shoe to support the shoe against movement in a widthwise direction as the upper is thus operated upon.

56. In a lasting machine, a rotary lasting device arranged to operate on a shoe controlled with respect to movement in a heightwise direction by the hands of the operator, said device comprising a gripper for gripping the margin of the upper at one side of the shoe and for pulling it inwardly over an insole as the device is rotated and having also means for wiping the margin of the upper inwardly over the insole by further rotation of the device, and means for engaging the upper at the other side of the shoe to support the shoe against movement in a widthwise direction as the upper is thus operated upon.

57. In a lasting machine, a shoe rest arranged to support a shoe presented with one side downward by engaging that side of the shoe underneath, and a lasting device arranged to operate on the upper located at the top side of the shoe thus presented while the shoe is controlled with respect to movement in a heightwise direction by the hands of the operator, said lasting device comprising means for gripping the margin of the upper and for pulling the upper and also means for laying the margin of the upper inwardly over an insole.

58. In a lasting machine, a shoe rest arranged to support a shoe presented with one side downward by engaging that side of the shoe underneath, and a rotary lasting device arranged to operate on the upper located at the top side of the shoe thus presented while the shoe is controlled with respect to movement in a heightwise direction by the hands of the operator, said lasting device comprising a gripper for gripping the margin of the upper and for pulling it in a downward direction over an insole as the device is rotated and also means for wiping the margin of the upper inwardly over the insole by further rotation of the device.

59. In a lasting machine, lasting means

arranged to operate on an upper at one side of a shoe, a shoe rest arranged to support the shoe against movement in a widthwise direction in the lasting operation by engaging the upper at the other side of the shoe, said shoe rest being yieldingly movable in that direction in response to pressure of the shoe against it when the shoe is presented to the machine, and means for thereafter locking the shoe rest against further movement in that direction.

60. In a lasting machine, a lasting device arranged to operate on an upper at one side of a shoe and comprising means for gripping the margin of the upper and for pulling the upper and also means for laying the margin inwardly over an insole, a shoe rest arranged to support the shoe against movement in a widthwise direction in the lasting operation by engaging the upper at the other side of the shoe, said shoe rest being yieldingly movable in that direction in response to pressure of the shoe against it when the shoe is presented to the machine, and means for thereafter locking the shoe rest against further movement in that direction.

61. In a lasting machine, power-operated lasting means arranged to operate on an upper at one side of a shoe, means for starting the power operation of the machine after the shoe has been presented to the machine, a shoe rest arranged to support the shoe against movement in a widthwise direction in the lasting operation by engaging the upper at the other side of the shoe, said shoe rest being yieldingly movable in that direction in response to pressure of the shoe against it when the shoe is presented to the machine, and automatic means for locking the shoe rest against further movement in that direction after the starting of the machine.

62. In a lasting machine, a power-operated lasting device arranged to operate on a shoe controlled with respect to movement in a heightwise direction by the hands of the operator, said device comprising a gripper for gripping the margin of the upper at one side of the shoe and for pulling the upper and also means for laying the margin of the upper inwardly over an insole, means for starting the power operation of the machine after the shoe has been presented to the machine, a shoe rest arranged to support the shoe against movement in a widthwise direction in the lasting operation by engaging the upper at the other side of the shoe, said shoe rest being yieldingly movable in that direction in response

to pressure of the shoe against it when the shoe is presented to the machine, and automatic means for locking the shoe rest against further movement in the same direction after the starting of the machine.

63. In a lasting machine, a shoe rest arranged to support a shoe presented with one side downward by engaging that side of the shoe underneath, a lasting device arranged to operate on the upper located at the top side of the shoe thus presented, said shoe rest being yieldingly movable downwardly in response to pressure of the shoe against it when the shoe is presented to the machine, and means for thereafter locking the shoe rest against further downward movement.

64. In a lasting machine, a shoe rest arranged to support a shoe presented with one side downward by engaging that side of the shoe underneath, a power-operated lasting device arranged to operate on the upper located at the top side of the shoe thus presented, means for starting the power operation of the machine after the shoe has been presented to the machine, said shoe rest being yieldingly movable downwardly in response to pressure of the shoe against it when the shoe is presented to the machine, and automatic means for locking the shoe rest against further downward movement after the starting of the machine.

65. In a lasting machine, a shoe rest arranged to support a shoe presented with one side downward by engaging that side of the shoe underneath, a power-operated rotary lasting device arranged to operate on the upper located at the top side of the shoe thus presented while the shoe is controlled with respect to movement in a heightwise direction by the hands of the operator, said lasting device comprising a gripper for gripping the margin of the upper and for pulling the upper and also means for wiping the margin of the upper inwardly over an insole as the device is rotated, means for starting the power operation of the machine after the shoe has been presented to the machine, said shoe rest being yieldingly movable downwardly in response to pressure of the shoe against it when the shoe is presented to the machine, and automatic means for locking the shoe rest against further downward movement after the starting of the machine.

CHARLES G. BROSTROM.
